(Cl. D56—4)

FIG. 1

The side of the record player opposite that shown in Figure 1 is identical thereto, the bottom of the device being unornamented.

I claim:

The ornamental design for a record player, substantially as shown and described.
